CLOCK ESCAPEMENT MEANS

Herman Naess, New Brighton, Staten Island,
and Sigfrid Strommer, New York, N. Y.

Application October 17, 1936, Serial No. 106,234

5 Claims. (Cl. 58—117)

This invention relates to clocks and more particularly to a novel escapement suitable for clocks, time switches, time fuses, shutter movements for cameras, tachometers and other timing devices. A primary object of the invention is to provide a novel escapement which is never locked but is always in position to start the moment power is applied and which cannot stop as long as power is supplied. Its construction also eliminates the hair spring, collet, stud, regulator, pallet and fork, pallet pins and dart, roller and other parts of the usual escapement mechanism, thereby effecting considerable economy in the manufacture of devices of the type set forth. This invention 15 templates an escapement that is never at rest, except for an instant at the end of each oscillation of the balance wheel, as long as the main spring is wound. In other words, the escapement means is powered only from the main spring, and 20 is so constructed that no hair spring or its equivalent is necessary to start or to complete each oscillation of the balance wheel.

Another object of the invention is to provide a balance or balance wheel having on one side thereof, eccentric to the balance staff, a novel impulse member, having curved faces intermittently in contact with the teeth on the escape wheel or wheels, which teeth are also of novel shape, permitting the impulse member to alternately clear the escapement teeth so that the balance wheel does not stop but may freely oscillate as long as power is supplied to the gear train from the main spring.

A further object is to provide a novel arrangement of escape wheels operating in conjunction with the balance and impulse pin which ensures reliable operation of the escapement without the aid of many of the usual parts required for that purpose.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawing, in which:—

Figure 1 is a vertical cross-sectional view of a clock mechanism embodying the present improvements.

Figure 2 is a detail sectional view taken on the line 2—2 of Fig. 1.

Figure 3 is a detail sectional view taken on the line 3—3 of Fig. 1.

Figure 4 is an inside face view of the balance wheel.

Similar reference characters designate corresponding parts throughout the several figures of the drawing.

According to the embodiment of the invention shown in the drawing the clock mechanism includes in its organization a main spring S which actuates the first or main wheel 1 which forms a part of a gear train designated generally as T and the escape wheels 2 and 3 which receive power through the train from the main spring. The escape wheels 2 and 3 are mounted on a shaft or arbor 4 journaled in the frame parts 5 and 5a as shown in Fig. 3.

The escape wheels 2 and 3 are provided with the teeth 2a and 3a respectively which are arranged in staggered relation. Each wheel usually includes fifteen teeth and all of the teeth are of the same shape, and therefore a description of one will suffice for all. Both faces of each tooth are substantially straight as indicated at c—c but lie in planes at an angle to each other, like a wedge, to provide a point or apical portion d. Under the influence of the main spring these teeth are intended to cooperate with an impulse member A carried by the balance or balance wheel B, as will presently appear. The balance wheel B is provided with a balance staff 6 which is journaled in the bracket portions 7 and 8 so that the balance staff 4 lies in a plane parallel to the escape wheels 2 and 3 and medially thereof. Therefore, the balance wheel B is mounted at right angles to the escape wheels 2 and 3.

The impulse member A is of substantially triangular or three-corner formation and is located on the inner face of the balance wheel eccentric to the axis of the staff 4 (see Figs. 2 and 4). The operative faces 9 and 10 of the impulse member A are curved as shown, or, in other words, are of concave formation. Preferably the faces 9 and 10 are formed on an arc whose radius is five millimeters, although it will of course be understood that this radius may vary for different sizes and types of construction. Thus, the impulse pin A has two concave impulse faces always in the path of the teeth 2a and 3a of the escape wheels and these faces are adapted to alternately contact with and receive impulse from the two escape wheels 2 and 3. When in action the balance wheel B oscillates through an arc of approximately 120° and it is always in position to start the moment power is applied to the train and cannot stop so long as power is furnished. Suitable safety means are provided to maintain

these conditions through the proper design of the width, form and position of the impulse member; the line on which the concave impulse faces meet being directly in line with the balance staff 5 and perfectly coinciding with the axis of said staff. The width of the impulse member is greater than the distance between the free ends of the teeth 2^a, 3^a of the respective wheels 2 and 3 by any suitable amount depending upon the 10 amount of angular movement of the balance wheel B that may be desired in any given case, and to prevent the balance wheel which carries the impulse member from swinging through too great an arc, and to keep it always in position to 15 receive an impulse from the next escape wheel tooth the opposite corners x and y of the member may strike against the corners of the bracket 7 as will be apparent from Fig. 3. In practice however, the arrangement of the teeth 2^a and 3^a and 20 the width of the member A usually is such that the balance normally describes the arc of 120° previously referred to.

When the main spring S is wound and the gear train T energized, the force of the spring will be 25 transmitted by the train to the escape wheels 2 and 3 and therefore they will turn in the direction of the arrow shown in Fig. 1. When, for example, the point or apex d of the teeth 3^a (Fig. 2) strike the impulse face 10, the balance 30 wheel B will be oscillated in the direction of the full line arrow in Fig. 2. When the apex on the tooth 3^a releases or clears the face 10 of the impulse member it will be apparent that the impulse member A has been moved so that its face 35 9 is in position to receive impact from the tooth 2^a (Fig. 2) of the wheel 2 whereupon the balance wheel will be oscillated in the direction of the dotted line arrow in Fig. 2. This operation is repeated each time the impulse member clears a tooth on one or the other of the escape wheels. Due to the fact that points d of the teeth bear 40 alternately against the concave surfaces 9 and 10, the power of the main spring will readily oscillate the balance wheel, and also due to the shape of the teeth, they will clear the corners x and y of the impulse member to permit the required movement of the balance and escape wheels. When the weight and diameter of the 45 balance wheel is in correct proportion to the power of the main spring the momentum developed by the balance wheel is the main regulating factor. The proportion of momentum to power tends to equalize the time of oscillation of the balance wheel. The frequency of oscillations can be determined by the weight and diameter of the balance wheel within very wide limits.

From the foregoing it will be apparent that the present invention provides an escapement construction wherein the balance wheel continuously 60 oscillates under power furnished solely from the main spring thereby eliminating the necessity for the hair spring and pallet, etc. as previously indicated.

We claim:—

1. An escapement mechanism comprising rotatably driven means including two annular series of teeth laterally spaced apart, the teeth of each series being alined with the spaces between the teeth of the other series, a balance 65 member disposed outwardly of said series of teeth, means extending laterally from said balance member toward said series of teeth and providing a pair of faces related to each other and to the axis of oscillation of said balance member 70 and to the teeth of said series so that one is to

be wiped and displaced by the teeth of one of said series to move the balance member in one direction and the other is to be wiped and displaced by the teeth of the other of said series to move the balance member in an opposite direction, and means restricting the movement imparted to the balance member by any given tooth of either series to an amount such that the next effective tooth of the other series cooperates with its related face on the balance member to reverse the movement of the latter before the last mentioned face can reach a position to permit the teeth of its related series to pass freely by the same, whereby the series of teeth may rotate continuously and whereby their continuous rotation effects oscillation of said balance member. 15

2. An escapement mechanism comprising a shaft to be driven, escapement wheel means on said shaft including two annular series of teeth laterally spaced apart, the teeth of each series being alined with the spaces between the teeth of the other series, an oscillatory balance member disposed outwardly of said series of teeth, means extending laterally from said balance member toward said series of teeth and providing a pair of faces related to each other and to the axis of oscillation of said balance member and to the teeth of said series so that one is to be wiped and displaced by the teeth of one of said series to move the balance member in one direction and the other is to be wiped and displaced by the teeth of the other series to move the balance member in an opposite direction, the annular spacing of the teeth of said series and the widths and dispositions of said faces being such that each newly acting tooth of each series operates with its related face first to stop the movement imparted to the balance member by the last acting tooth of the other series and then to impart movement to the balance member in an opposite direction whereby the series of teeth may rotate continuously and whereby their continuous rotation effects oscillation of said member. 30

3. As escapement mechanism as set forth in 45 claim 2 in which the faces are disposed between the teeth in divergent relationship as regards the direction of rotation of the teeth, and in which the distance between the far edges of said faces as regards the direction of rotation of the teeth 50 is greater than the distance between the teeth of the respective series.

4. An escapement mechanism comprising a shaft to be driven, escapement wheel means on said shaft including two annular series of teeth laterally spaced apart, the teeth of each series being alined with the spaces between the teeth of the other series, an oscillatory balance member disposed outwardly of said series of teeth for rotation in a plane at right angles to the planes of 60 rotation of said series of teeth and about an axis intersecting the axis of said shaft, means extending laterally from said balance member toward said series of teeth and providing a pair of faces related to each other and to the axis of 65 oscillation of said balance member and to the teeth of said series so that one is to be wiped and displaced by the teeth of one of said series to move the balance member in one direction and the other is to be wiped and displaced by the 70 teeth of the other series to move the balance member in an opposite direction, the annular spacing of the teeth of said series and the widths and dispositions of said faces being such that each newly acting tooth of each series operates 75

with its related face first to stop the movement imparted to the balance member by the last acting tooth of the other series and then to impart movement to the balance member in an opposite direction whereby the series of teeth may rotate continuously and whereby their continuous rotation effects oscillation of said member.

5. An escapement mechanism as set forth in claim 4 including a frame element by which the

balance member is supported, said frame element having stop formations to be engaged by the means extending from the balance member and providing the faces to be wiped and displaced by the teeth of the escapement wheel means to limit the arc of oscillation of the balance member. 5
